UNITED STATES PATENT OFFICE

CHARLES R. GRIFFITH, OF SOUTH MANCHESTER, CONNECTICUT

SEDIMENTATION TANK

Application filed May 10, 1928. Serial No. 276,683.

This invention relates to means for reclaiming valuable matter from domestic sewage and industrial waste waters, and the primary object is to provide a novel construction of 5 tank of the "fill and draw" type by the use of which the particles of matter in suspension in the water will be precipitated by the action of gravity alone, and the water and sludge may be separately drawn off at proper intervals. 10 The invention is illustrated in the accompanying drawings and will be hereinafter fully described, and it consists in certain novel features which will be particularly pointed out in the appended claims.

15 In the drawings:

Figure 1 is a plan view of a tank embodying the invention;

Figure 2 is a central vertical longitudinal section;

20 Fig. 3 is a sectional elevation of the discharge end of the tank,

Figure 4 is a detail of an inlet,

Figure 5 is a horizontal section.

In the practice of the invention, there is 25 built a concrete tank 1 of oblong form of desired dimensions and the walls of which may have metallic reinforcements embedded therein. At the outlet end of the tank, a sludge-discharge opening 2 is formed through 30 the end wall and a sludge sump 3 is formed in the floor of the tank to discharge through said opening, the floor 4 being inclined from all points toward said sump, as will be understood on reference to Figs. 2 and 3. Adjacent the inlet end of the tank, a weir 5 is built 35 transversely as an integral part of the floor, a receiving and distributing trough 6 being thereby formed between the weir and the adjacent wall 7 of the tank. Inlet openings 8 are formed through the wall 7 and an influent 40 canal 9 is built along the outer side of said wall to bring the laden water to said openings through which it will flow into the trough in an obvious manner, and a roof 10 is pref- 45 erably formed over the canal to provide a convenient footing for the attendants although it is obvious the wall 7 may be thick enough to furnish a safe footing. A gate valve 11 of any approved detail form is provided to control the flow through each of the

openings 8, each valve being slidably mounted in a guide frame 12 and having a stem 13 rising through the top of the frame. The frames 12 are fixed to the wall, in any approved manner and project above the same, as shown, and resting on the top bar of each frame is a nut 14 having threaded engagement with the upper threaded portion of the respective stem 13. The nut 14 may advantageously take the form of a hand wheel and it will be readily understood that, accordingly as the wheel is rotated in one or the opposite direction, the valve will be raised to permit flow or lowered to cut off flow through the opening controlled by it.

The inlet opening 8 is located on a level with the bottom or floor of the canal 9 but is above the floor of the trough or channel 6 and around each opening a baffle 15 is secured upon the tank wall with its open lower end spaced from the floor of the trough. The baffles prevent the inflowing liquid from flowing directly over the weir and direct it to the floor of the trough so that it will be evenly distributed and will flow over the weir steadily and slowly in a relative thin stream, some agitation of the liquid occurring as a result of the impact upon the baffles whereby some pulverization of the matters in suspension will be effected.

Some matter carried by the water will settle upon the floor of the trough and may be washed out from time to time through an opening 16 in one end of the trough and constituting one terminal of a by-pass 17 in the side wall of the tank. This by-pass discharges into the tank at the inner side of the weir, and a gate-valve 18 is arranged to cover or uncover the outlet end of the by-pass through the manipulation of a lever 19 which projects above the side wall of the tank for convenient operation. It will be understood that if the valve be set in open position, the water entering the trough will flow into and through the by-pass so that any sediment which may have previously collected in the trough will be carried into the main chamber of the tank to be eventually delivered into the sludge sump.

Flow through the sludge outlet 2 is con-

trolled by a gate valve 20 mounted in any convenient manner at the inner end of the outlet and carried by a rod 21 which extends to the top of the adjacent wall and is there connected to a suitable lever 22 or other setting device. Above the level of the top of the sludge sump, a series of water-outlets 23 extends through the tank wall to deliver into the effluent canal 24 leading to a point of de-
10 posit or use, it being noted that the outlet 2 passes under the canal. The discharge through each outlet is controlled by a gate valve 25 from which a rod 26 rises to the top of the wall where it is connected to a lever
15 27 or other setting device.

On the inner side of the tank wall over each outlet opening is a frame 28 including grooved side members 29, and slidably mounted in said side members are a screen
20 30 and a floating baffle 31, each screen comprising a coarse mesh metallic netting to act as a support and a fine fabric sheet covering the inner surface of the netting. The baffle may fit in the frame so as to slide easily but
25 the screen should fit closely so that the water must pass through it and can not pass around it, and it will be noted that the screens are spaced from the wall by the frames 28 to provide channels through which the water
30 may pass to the outlets while the floating baffle rises and falls with the level of the water to prevent scum and other surface matter adhering to the screen. The screen may be cleaned by passing water therethrough in
35 the opposite direction or in a downward direction on its inner side. In order that the screens may be raised for inspection or repair, a trolley frame 32 is erected on the end wall of the tank and a trolley 33 is mounted to travel along the top of said frame, said trolley being equipped with a hoisting cable and a block and tackle 34 which may be engaged with the screen to be raised.

In use the outlets are closed and the inlets
40 are opened and kept open until the tank is filled whereupon they are closed and the body of water permitted to stand in a quiescent state for a period determined by the nature of the liquid being treated. At the
50 end of the settling period, the draw-off valves 25 are opened and the water will then pass through the screens, which act as a filter, and flow off through the effluent canal. The process is then repeated, the inflowing water
55 scouring the floor of the tank and depositing sludge into the sump from which it is drawn by gravity or a pump at given intervals to prevent septic action which should never be permitted, and the periods of withdrawal
60 will depend on the nature of the sludge. In the case of domestic sewage or the like in which the sludge quickly decomposes, the liquor should never be allowed to remain in the tank beyond the necessary quiescent
65 period. At night or when the flow is low,

the sludge in the tanks that are not being filled may be left exposed to the air as septic action may be thereby retarded for a considerable period specially in cold weather. It is advisable to provide a plurality of tanks so that some may be filled while others are settling, and, of course, under some weather conditions, the tank may be covered.

Having fully described my invention what I claim as new and desire to secure by Letters Patent, is:—

1. Apparatus for the purpose set forth comprising a tank having means at one end for separately drawing off liquor and sludge, inlets extending through the opposite end of the tank, a weir adjacent said end, a shallow trough between the inlets and the weir and a by-pass in the lateral side of the tank around the end of the weir and establishing communication between an end of the trough and the main settling chamber of the tank.

2. Apparatus for the purpose set forth comprising a tank having means at one end for separately drawing off liquor and sludge, inlets extending through the opposite end of the tank, a weir adjacent said end, a trough between the inlets and the weir, a by-pass around the end of the weir in the side of the tank establishing communication between an end of the trough and the main settling chamber of the tank, a valve controlling flow through the by-pass, and means operable from the top of the tank for setting the valve.

3. Apparatus for the purpose set forth comprising a tank having inlets at one end and a sludge sump at the opposite end, a valved outlet for the sump, valved outlets for liquor above the sump, screens over the last-mentioned outlets, and floating baffles at the inner sides of the screens.

In testimony whereof, I have signed this specification.

CHARLES R. GRIFFITH.
